CLAIM

The ornamental design of a combined stackable tray and shipping carton, as shown and described.

DESCRIPTION

FIG. 1 is a perspective view of a combined stackable tray and shipping carton according to the inventive design in the form of a glued blank;

FIG. 2 is a top plan view thereof;

FIG. 3 is a front elevational view thereof;

FIG. 4 is an elevational view of one side, the other side being a mirror image thereof;

FIG. 5 is a bottom plan view thereof; and,

FIG. 6 is a perspective view of the combined stackable tray and shipping carton after the glued blank therefor has been erected.

The broken line showing on FIGS. 1, 3 and 6 represent fold lines.
